(57) **CLAIM**

The ornamental design for a hair dye kit, as shown and described.

DESCRIPTION

FIG. 1 is a front elevational view of the hair dye kit of the present invention;

FIG. 2 is a rear elevational view of the hair dye kit of FIG. 1;

FIG. 3 is a left side elevational view of the hair dye kit of FIG. 1;

FIG. 4 is a right side elevational view of the hair dye kit of FIG. 1;

FIG. 5 is a top plan view of the hair dye kit of FIG. 1; and, FIG. 6 is a bottom plan view of the hair dye kit of FIG. 1. The structures shown in broken lines are for illustrative purposes only and form no part of the claimed design.
